(57) **CLAIM**

The ornamental design for a expandable closure for waistbands, as shown and described.

DESCRIPTION

FIG. 1 is a front elevational view of a expandable closure for waistbands showing my new design;

FIG. 2 is a rear elevational view thereof;

FIG. 3 is a side view, taken from the left side of FIG. 1;

FIG. 4 is a side view, taken from the right side of FIG. 1; and,

FIG. 5 is a top plan view thereof, the bottom plan view being a mirror image thereof.
